UNITED STATES PATENT OFFICE.

FREDERICK W. PHILLIPS, OF LYNN, MASSACHUSETTS, ASSIGNOR TO UNITED SHOE MACHINERY CORPORATION, OF PATERSON, NEW JERSEY, A CORPORATION OF NEW JERSEY.

SHOE-TREATING APPARATUS.

Application filed October 17, 1923, Serial No. 669,190, and in Canada December 5, 1922.

This invention relates to apparatus for treating shoes in process of manufacture to soften the uppers and the stiffening members incorporated therein preparatory to shaping the uppers to the lasts. It is now customary to subject each shoe to a first softening treatment prior to the pulling-over operation, and to a second softening treatment prior to the lasting operation. The invention is herein disclosed in a form more especially adapted to perform the second softening operation, the upper at that time being pulled over and temporarily fastened to the bottom of the last, but it will be evident that the invention is also capable of use in a form of apparatus designed more especially to perform the first softening operation.

In modern methods of shoemaking it has been demonstrated that moderately hot water-vapor is the most effective medium to render the upper pliant for pulling over and lasting and this is true even when the stiffening members are made of a well-known prepared material that becomes soft when heated without being moistened, because moisture rather than heat is required to make the upper leather pliant enough to be satisfactorily crimped and shaped around the toe. On the other hand, an excessive quantity of moist vapor is detrimental to some leathers and is objectionable in that it renders the atmosphere of the work-room uncomfortable and unhealthful. Many and various types of apparatus have heretofore been devised to supply hot vapor for the purpose stated, but they have been attended with problems in which condensation, excessive heat, and excessive quantities of vapor have made it difficult, if not impossible, to attain the most desirable results and the most efficient working.

In view of the difficulties and problems above mentioned an object of the invention is to provide an improved softening apparatus by which the quantity of moist vapor and its temperature may be regulated more closely to the requirements of such work, and by which the vapor may be localized at the treating stations to a greater extent than heretofore. In this respect a feature of the invention consists in localizing an individual heater under and adjacent to each of a plurality of treating stations and supplying water, preferably hot water, to each of said heaters to provide an individual supply of vapor for

each treating station. As herein shown, the invention therefore provides an apparatus comprising a plurality of treating stations and an individual flash-boiler for each of said stations.

Another object of the invention is to provide improved means for feeding water in suitable volume to points adjacent to the work-stations where it is to be converted into vapor. Furthermore, to expedite vaporization of the water it is preferable to supply hot water to the individual vaporizers. Therefore, the invention provides means by which heat energy may be utilized to propel the water at atmospheric pressure to the vaporizers incidentally to raising the temperature of the water. Said means is hereinafter termed "thermo-motive means" and includes a small boiler and a steam bubbling fountain.

Since the boiler necessarily produces some vapor incidentally to supplying water to the individual vaporizers a feature of the invention consists in locating it so that said vapor will be used to treat the work.

Still another object of the invention is to provide improved means for regulating the quantity of vapor produced by the individual heaters adjacent to the treating stations. These heaters are preferably formed and arranged to shed the water that is supplied to them and to vaporize more or less of the water while it is flowing from the points where it is supplied to the points where it is shed. If, then, a quantity of water in excess of that actually required for vapor is supplied to flow over each heater a proportion of it will be converted into vapor and the remainder will be shed. The proportion of water vaporized may therefore be varied by varying the quantity that is shed, and the proportion shed may be varied either by varying the rate of speed at which the water flows over the heater or by varying the area over which it must flow while in contact with the heater.

Preferably this regulating may be effected by increasing and decreasing the length of the path traversed by the water flowing on the heater, and a feature of the invention consists in providing for relative adjustment of the heater and the water-supplying means to vary the length of said path. An advantage in regulating the vapor output this way is that fluctuation in the volume of water-supply does not produce any substantial varia-

tion in the vapor output, since the quantity of water shed by the heater will automatically vary according to variations in the quantity supplied while the vapor output will 5 remain substantially constant so long as there is no increase or decrease in the distance to be traversed by the water in flowing on the heater.

The invention also provides for returning 10 the surplus water from the individual vaporizing heaters to the boiler with which the steam bubbling fountain cooperates. The water for supplying the vaporizing heaters is therefore kept in circulation while portions 15 of it are being converted into vapor adjacent to the treating localities. The water thus circulated is maintained at a high temperature requiring only a slight increase by the individual vaporizing heaters to produce the 20 vapor.

Other features of the invention are illustrated by the accompanying drawings and are hereinafter described and claimed.

Referring to the drawings, 25 Fig. 1 is a side view, partly in section and partly in elevation, of a preferred form of apparatus embodying this invention and including the forepart of a shoe in position for treatment;

30 Fig. 2 is a vertical section through the structure intersected by line 2—2 of Fig. 1; and

35 Fig. 3 is a top view partly in section, the front of the apparatus being at the bottom of the figure.

The illustrated apparatus comprises preferably a cast iron base 10 which constitutes the greater part of the casing for enclosing the working parts. The upstanding walls 11 40 and a horizontal wall 12 provide an open topped reservoir for cold water. The central part of the reservoir is provided with an annular upstanding wall 13 that forms a well to contain a boiler 14 so that the reservoir and the boiler may be arranged in nested relation.

Individual treating stations are formed by a series of cowls 15 and are separated from each other by partitions 16. These elements 50 are preferably cast en bloc and fastened to the top of the walls 11. The bottoms of the treating stations are formed by foraminous plates 17 the marginal portions of which rest on flanges projecting from the cowl structure.

55 An adjustable table 18 is provided for supporting a series of shoes arranged side by side, and forms a cover for the forward part of the water reservoir. The work-support is mounted on pivot members 19 adjacent to the 60 cowl member and is adapted to occupy various positions of adjustment with respect to movement about the axis of the pivot members. A bar or strip 20 is connected to the table by a pivot member 21 and is provided 65 with a series of teeth 22 any one of which

may cooperate with a stationary pin 23 to maintain the table at the desired angle of inclination.

Individual heaters 25 are provided for the treating stations respectively and are arranged under the stations to heat the work by upward radiation. According to the illustrated design these heaters are in the form of shells and are suitably proportioned to contain electric heating units of standard cylindric type. The heaters 25 are designed to function also as flash-boilers to furnish vapor to treat the work, and for this purpose they are preferably provided with trough portions 70 26 in which the water may flow while being heated. The trough portions are preferably inclined as shown by Fig. 1 to shed the water, but the degree of inclination is slight and the water does not drain so rapidly as to restrict vaporization unduly. Since the trough portions 75 26 are under and adjacent to the treating stations respectively each treating station receives an individual supply of vapor which has so short a distance to travel from the vaporizing locality to the work that a high 80 degree of efficiency is maintained.

The apparatus also includes thermo-motive means for supplying individual streams of water to the troughs 26, the boiler 14 being an element of said means. The boiler is a 85 cup-shaped receptacle and is preferably open at the top. Some hot water-vapor will, of course, rise through the top of the boiler and flow between two of the heaters 25 (see Fig. 2) to the shoes supported over said heaters 90 by the table 18. To all intents and purposes the boiler is thermally insulated from the structure forming the water reservoir and is supported by ears 27 fastened to the bottom 12 of the reservoir by screws. Water 105 flows by gravity from the reservoir into the boiler through a pipe 28 and maintains the same level in the boiler as in the reservoir. The bottom of the boiler is provided with chambers 29 for containing electric heating 110 units of standard cylindric type. The mass to be heated by these units is so small that initially cold water can be caused to boil in the space of a few minutes and will thereafter be maintained at a boiling temperature 115 with comparatively little current consumption.

The thermo-motive means for supplying water to the individual vaporizing heaters 120 25 comprises, in addition to the boiler 14, a device adapted to utilize the force of ebullition to elevate the water from the level of the water reservoir to or above the level of the heating troughs 26. For convenience this 125 device is hereinafter termed a "steam bubbling fountain." It comprises a dome-shaped member 30 and a standpipe 31 leading therefrom. The rim of the member 30 rests on the bottom of the boiler and is provided with notches to afford adequate circulation of 130

water. Since the bottom of the boiler is the hottest part of the water under the member 30 boils with a high degree of energy and the bubbles of steam rising in the pipe 31 lift the hot water in a series of small bodies to the top of the pipe.

For the purpose of distributing the hot water equally to the vaporizing heaters 25, of which there are four in the illustrated apparatus, the top of the standpipe 31 is provided with two branches 32 extending horizontally in opposite directions. Further distribution of the water is effected by channel members 33 supplied by the branches 32 respectively. Each member 33 has a main channel 34 and two branch channels 35. The discharging ends of the channels 35 are arranged over the troughs 26 respectively.

The water-supplying apparatus above described is capable of supplying the individual vaporizing heaters 25 with more than enough water to furnish the maximum quantity of vapor required, and since the surplus water drains from the troughs 26 provision is made to return the surplus to the boiler 14 for subsequent use. Accordingly draining troughs 36 are arranged to receive the water shed by the troughs 26. The troughs 36 are preferably inclined and their discharge ends 30 are located over the boiler.

Some of the water is kept in circulation by the above-described apparatus and is maintained at a temperature that requires comparatively little additional heat from the heaters 25 to convert it into vapor. The water-reservoir and pipe 28 automatically replenish the boiler to compensate for the water taken out by vaporization.

The illustrated apparatus also provides for regulating the vapor output of the troughs 26 by altering the extent to which the water may flow on them. For this purpose the channel members 33 are arranged to be adjusted lengthwise of the troughs 26. The channel members 33 are arranged to slide on stationary supporting rods 37 respectively. Operating rods 38 are fastened to the members 33 and extend laterally through slots 39 in the side walls 11 of the casing. Knobs 40 are attached to the outer ends of the rods 38 and afford convenient means by which the members 33 may be adjusted toward and from the draining ends of the troughs 26. When the channel members 33 are adjusted to discharge the water at points relatively distant from the draining ends of the troughs 26 the water flowing on the heaters has a greater distance to flow before reaching the draining points and remains in contact with the heaters for a greater length of time. Consequently a greater proportion of the water will be vaporized and a correspondingly smaller proportion will be drained. If the quantity of vapor is more than needed it may be diminished by shifting the members 33 to

discharge the water into the troughs 26 at points nearer the draining ends of the troughs. This will shorten the paths of the water on the heaters and will also shorten the length of time during which the water remains in contact with the heaters. The range of adjustment of the members 33 is sufficient to permit shifting the discharging ends into vertical register with the draining troughs 36, and when the members 33 are in that position no water is vaporized by the heaters 25 but continues nevertheless to circulate, provided the bubbling fountain continues to operate.

Each adjusting rod 38 is provided with a frictional device for maintaining the position of adjustment against the tendency of shop vibration to shift the members 33. Each of said devices comprises a collar 41 loosely surrounding the rod and pressed against the outside surface of the adjacent wall of the casing by a compression spring 42.

Since the vaporizing heaters 25 are grouped in pairs, and since each pair is supplied with water by a single adjustable member 33, it is possible to regulate the treatment at one pair of treating stations independently of the treatment at the other pair of stations. In fact, one of the adjustable members 33 may be placed in a position that will eliminate vaporization entirely while the other may be placed to provide for any desired quantity of vapor. The regulations with respect to the quantity of vapor, no matter what they may be, have no effect on the operation of the thermo-motive means for circulating the water, the latter continuing to operate under all conditions excepting as the quantity of water circulated may be varied by regulating the heating effect of the electric units in the chambers 29.

Any preferred controlling apparatus may be provided to regulate the temperature of the individual heaters 25 and the electric heating units embedded in the bottom of the primary boiler 14. For example, the drawings illustrate a three-way switch 45 for controlling the heating units by which the primary boiler is operated, and this circuit may be independent of the circuits including the electric units in the heaters 25. The three-way switch 45 and the heating units for the boiler 14 are so connected that by turning the knob of the switch to one position current will be furnished to both heating units to start the operation of the boiler. By turning the knob of the switch to another position one of the heating units may be cut out while the other continues to operate the boiler. Turning the knob of the switch to still another position will disconnect both heating units. Two independent switches 46 and 47 are provided for controlling the circuits that operate the vaporizing heaters 25, each pair of said heaters being under the control of one

of these switches. Furthermore, a rheostat 48 is included in the circuit controlled by the switch 46 while a rheostat 49 is included in the circuit controlled by the switch 47. This affords regulation of the heating effect of one pair of heaters 25 by the rheostat 48 while the heating effect of the other pair of heaters 25 may be regulated by the rheostat 49. If the character of the work is such that no vapor is required the switch 45 will be left in a position to cut out both heating units of the boiler 14 and the switches 46 and 47 will be set to turn on the current for the units in the individual heaters 25 subject to regulation by the rheostats 48 and 49. The apparatus will then supply radiant heat exclusively.

Having thus described my invention, what I claim as new and desire to secure by Letters Patent of the United States is:—

20 1. A shoe-treating apparatus comprising means forming a treating station, a heater adjacent thereto, a reservoir for water at atmospheric pressure, and thermo-motive means arranged to supply water from said reservoir to said heater to furnish vapor for treating the work.

30 2. A shoe-treating apparatus comprising means forming a treating station, a heater adjacent thereto, an open reservoir for cold water at atmospheric pressure, and means including a steam bubbling fountain arranged to receive cold water from said reservoir by gravity and to supply hot water to said heater to furnish vapor for treating the work.

40 3. A shoe-treating apparatus comprising a flash-boiler for generating treating vapor, means for supporting an article of work adjacent to said flash-boiler for treatment, a primary boiler at a level lower than said flash-boiler, and means including a steam bubbling fountain for supplying hot water from said primary boiler to said flash-boiler to be vaporized by the latter.

45 4. A shoe-treating apparatus comprising means forming a treating station for the work, heating means arranged adjacent to said treating station for generating treating vapor, a boiler arranged at a level lower than said heating means, and means including a steam bubbling fountain for supplying hot water from said boiler to said heating means to be vaporized by the latter.

55 5. A shoe-treating apparatus comprising means forming a treating station, an open boiler arranged under said treating station to supply vapor for treating the work, a heater arranged between said boiler and the work-station, and means for supplying hot water from said boiler to said heater to furnish additional vapor for treating the work.

60 6. A shoe-treating apparatus comprising means forming a series of treating stations for individual articles of work, an open boiler arranged under said treating stations to sup-

ply vapor for treating the work, a series of heaters located under and adjacent to said treating stations respectively, and means for supplying hot water from said boiler to said heaters to furnish individual supplemental supplies of vapor to the treating stations respectively.

70 7. A shoe-treating apparatus comprising means forming a series of treating stations for individual articles of work, a series of heaters located under and adjacent to said stations respectively, and means including a boiler and a steam bubbling fountain for supplying hot water to said heaters to furnish individual supplies of vapor to the treating stations respectively.

75 8. A shoe-treating apparatus comprising means forming a treating station, an open boiler arranged under said station to supply vapor to treat the work, a heater arranged under said station but above said boiler to re-heat said vapor, and a steam bubbling fountain for supplying hot water from said boiler to said heater to furnish a supplemental quantity of vapor for the work.

80 9. A shoe-treating apparatus comprising means forming a treating station, a heater adjacent thereto, means including a boiler arranged to supply hot water to said heater to furnish vapor for treating the work, and means arranged to return any excess of hot water from said heater to said boiler.

85 10. A shoe-treating apparatus comprising means forming a series of treating stations, a series of heaters arranged adjacent to said stations respectively, means including a boiler for supplying hot water at atmospheric pressure to each of said heaters to furnish vapor for treating the work, said boiler being below the level of said heaters, and means for draining any excess of water from said heaters and returning it to said boiler.

90 11. A shoe-treating apparatus comprising means forming an open water-circuit, means for circulating water at atmospheric pressure, means forming a treating station adjacent to a point in the water-circuit, and heating means arranged to vaporize some of the water at said point to supply said station with vapor for treating the work.

95 12. A shoe-treating apparatus comprising means forming an open water-circuit including thermo-motive means for heating and circulating water at atmospheric pressure, means forming a treating station adjacent to a point in the water-circuit, and heating means adjacent to said treating station for vaporizing some of the water in circulation to supply vapor for treating the work.

100 13. A shoe-treating apparatus comprising means forming a treating station, a heater adjacent to said station, said heater having a trough for converting water into vapor to treat the work, means including a boiler to

supply water at atmospheric pressure to said trough, and means arranged to return surplus water from said trough to said boiler.

14. A shoe-treating apparatus comprising means forming a treating station, a heater adjacent to said station for converting water into vapor to treat the work, thermo-motive means to supply water to said heater, and means arranged to return surplus water from 10 said heater to said thermo-motive means for subsequent use.

15. A shoe-treating apparatus comprising means forming a treating station, a heater arranged adjacent to said station for converting water into vapor to treat the work, thermo-motive means arranged to supply water from a lower level to said heater to be vaporized, and means arranged to drain surplus water from said heater back to said thermo-motive means for subsequent use.

16. A shoe-treating apparatus comprising means forming a treating station, a heater adjacent to said station for converting water into vapor to treat the work, means including 25 an open boiler adjacent to said station and a steam bubbling fountain for transferring hot water at atmospheric pressure from said boiler to said heater to be vaporized, and means for automatically replenishing the 30 water in said boiler.

17. A shoe-treating apparatus comprising means forming a treating station, a heater adjacent to said station for converting water into vapor to treat the work, means including 35 an open boiler and a steam bubbling fountain for transferring hot water at atmospheric pressure from said boiler to said heater to be vaporized, a water-reservoir thermally insulated from said boiler and arranged substantially at the boiler level, and a conduit 40 arranged to maintain the water level in said boiler at the same height as that in said reservoir.

18. A shoe-treating apparatus comprising 45 means forming a treating station, a heater adjacent to said station for converting water into vapor to treat the work, thermo-motive means for supplying hot water to said heater to be vaporized, and a water-reservoir surrounding but thermally insulated from said thermo-motive means to replenish the latter with water by gravity.

19. A shoe-treating apparatus comprising 55 means forming a treating station, a heater adjacent to said station for converting water into vapor to treat the work, an open boiler at a level lower than said heater, and a conduit arranged to supply hot water from said boiler to said heater, the receiving end of said conduit being arranged in the water-space and adjacent to the bottom of the boiler to lead the water upwardly under the propulsive energy of the steam bubbles.

20. A shoe-treating apparatus comprising 65 means forming a water-circuit and water-

circulating means including one or more heaters for converting a proportion of the circulating water into vapor to treat the work, and means constructed and arranged to replenish said water-circuit automatically 70 with additional water at a rate substantially commensurate with the rate of vaporization.

21. A shoe-treating apparatus comprising one or more heaters for converting water into vapor adjacent to one or more treating stations, means forming a water-circuit and water-circulating means including an open boiler for supplying hot water at atmospheric pressure to said heater or heaters, and means constructed and arranged to replenish 75 said boiler automatically with additional water at a rate substantially commensurate with the rate of vaporization.

22. A shoe-treating apparatus comprising a water-shedding heater for converting water into vapor to treat the work, and means for supplying water to flow on said heater, said heater and supplying means being relatively adjustable to vary inversely the shedding and vaporizing of water.

23. A shoe-treating apparatus comprising a heater for converting water into vapor to treat the work, said heater having a water-draining trough, and means for supplying water to said trough, said heater and supplying means being relatively adjustable to vary inversely the draining of said trough and the vaporizing of water.

24. A shoe-treating apparatus comprising a heater for converting water into vapor to treat the work, said heater being formed and arranged to shed water at a predetermined locality and to drain the water toward said locality, and means for supplying water to flow on said heater, said heater and supplying means being relatively adjustable to vary the length of time during which the water will remain in contact with the heater in flowing from the point of supply to the shedding locality.

25. A shoe-treating apparatus comprising a heater for converting water into vapor to treat the work, said heater having a trough formed and arranged to drain the water to a predetermined point and to discharge surplus water at said point, and means for supplying water to said trough to be vaporized, said heater and supplying means being relatively adjustable to vary the distance between the point of supply and said point of discharge.

26. A shoe-treating apparatus comprising a heater for converting water into vapor to treat the work, said heater having an inclined vaporizing portion, and means for supplying water to flow on said inclined portion, said heater and supplying means being relatively adjustable to shift the point of supply up and down said inclined portion.

27. A shoe-treating apparatus comprising

a heater for converting water into vapor to treat the work, said heater having a draining trough the bottom of which is inclined, and means for supplying water to said trough, 6 said heater and supplying means being relatively adjustable lengthwise of said trough.

28. A shoe-treating apparatus comprising a series of heaters for converting individual bodies of water into vapor to treat the work, 10 and means for supplying a plurality of individual streams of water to flow on said heaters respectively, said heaters being formed and arranged to shed the water not vaporized, and said heaters collectively and said means 15 being relatively adjustable to vary inversely the proportions of water drained and water vaporized.

29. A shoe-treating apparatus comprising heating means having a plurality of individual draining receptacles for converting water into vapor to treat the work, and means for supplying individual streams of water to 20 said receptacles respectively, said receptacles collectively and said supplying means being relatively adjustable to vary inversely the 25 proportions of water drained and water vaporized.

30. A shoe-treating apparatus comprising a plurality of heaters each having a draining trough for converting water into vapor to treat the work, means forming a source of supply for water, and means for distributing water from said source of supply to said troughs respectively, said distributing means 35 including an adjustable member by which water is supplied to a plurality of said troughs and by which the points of supply may be shifted toward and from the draining points of the troughs.

40. 31. A shoe-treating apparatus comprising a plurality of groups of heaters for converting water into vapor to treat the work, a source of water-supply, and water-distributing means comprising a plurality of individually adjustable members arranged to deliver water to flow on the heaters of the groups respectively, said heaters being formed and arranged to shed the water and said members being adjustable to shift the 45 points of delivery for the purpose of varying the vapor output of the heaters.

32. A shoe-treating apparatus comprising a series of pairs of heaters for converting water into vapor to treat the work, each pair of heaters having a pair of parallel draining troughs for the water, and water-supplying means comprising channel members arranged between the heaters of said pairs respectively, each of said channel members being adapted 55 to deliver water to the two troughs adjacent to it and being adjustable lengthwise of the troughs to vary inversely the proportions of water vaporized and water drained.

60. 33. A shoe-treating apparatus comprising water-shedding heating means for converting

water into vapor to treat the work, a casing, means in said casing for supplying water to flow on said heating means, said supplying means including an adjustable member for shifting the delivery point or points of the 70 water toward and from the shedding point or points of said heating means, and adjusting means extending through said casing to be operated externally for shifting said adjustable member. 75

34. A shoe-treating apparatus comprising a series of individual heaters for converting water into vapor to treat the work at a series of stations, a relatively broad and shallow water-reservoir underlying said heaters and having a substantially central well, means for supplying water to flow on said heaters, said supplying means including a boiler arranged in said well and a connection for enabling water to flow from said reservoir into said 80 boiler, and means for draining surplus water from said heaters back to said boiler for subsequent use. 85

35. A shoe-treating apparatus comprising a plurality of individual heaters for converting water into vapor to treat articles of work individually at separate stations, and means for supplying individual streams of water to said heaters respectively, said means including an adjustable member for changing 90 the course of one or more of said streams independently of one or more other streams to vary the vapor output of one or more of said heaters independently of the vapor output of one or more other heaters. 95

36. A shoe-treating apparatus comprising means forming a treating station, a heater adjacent thereto, and means adjacent to the treating station for boiling a liquid at atmospheric pressure and supplying the same to said heater by the action produced in boiling. 100

37. A shoe-treating apparatus comprising means for supporting the work, a heater for boiling water under the work station, means for supplying water to said heater, a secondary heater for vaporizing water adjacent to the work station, and means arranged to supply to said secondary heater, by the boiling action of said primary heater, a portion of the water boiled by the latter. 110

38. A shoe-treating apparatus comprising a water-reservoir having an interior upstanding wall forming an air space surrounded by the water space, a heater arranged in said air space, a conduit arranged to supply water from said reservoir to said heater to be heated, and means for supporting the work over said heater to be treated by the vapor rising therefrom. 120

39. A shoe-treating apparatus comprising work-supporting means, heating means arranged adjacent to the work station, and water-circulating means for supplying running water to said heating means to furnish vapor for treating the work, the two latter 125

said means being relatively adjustable to regulate the quantity of vapor irrespective of any surplusage of water circulated.

40. A shoe-treating apparatus comprising work-supporting means, heating means arranged under the work station, and means for supplying running water to said heating means to furnish vapor for treating the work, the two latter said means being relatively 10 adjustable to vary the quantity of vapor irrespective of any surplusage of water supplied.

41. A shoe-treating apparatus comprising work-supporting means, means for heating 15 the work, and water-circulating means including said heating means for supplying water to furnish vapor for treating the work, the two latter said means being organized to limit the quantity of vapor irrespective of 20 the quantity of water circulated and irrespec- tive of the degree of heat developed.

42. A shoe-treating apparatus comprising means forming a water-circuit and including heating means arranged to circulate the water 25 and vaporize a portion thereof in the atmosphere, and means arranged to support the work adjacent to a point in said circuit where the vapor is liberated from the water.

43. A shoe-treating apparatus comprising 30 a plurality of work-stations, a plurality of flash-boilers arranged adjacent to said stations respectively, and means for heating water at atmospheric pressure and for thereby supplying hot water to said flash-boilers 35 individually to furnish individual supplies of vapor to the work-stations.

44. A shoe-treating apparatus comprising work-supporting means, and means forming an open water-circuit, the latter said means 40 including water-circulating means and a heater arranged to supply radiant heat to the

work and to evaporate some of the water flowing in said circuit.

45. A shoe-treating apparatus comprising means arranged to support a shoe for treatment, an open reservoir for cold water at atmospheric pressure, a heater arranged above the level of said reservoir, both said reservoir and said heater being arranged to underlie the shoe, and means arranged to supply water from said reservoir to said heater to be converted into vapor by the latter, said water-supplying means including a boiler thermally insulated from said reservoir and arranged to raise the water to or above the 50 level of said heater by the force of ebullition.

46. A shoe-treating apparatus comprising a water-reservoir and an open topped boiler arranged in nested relation but thermally insulated from each other, a conduit forming communication between said boiler and said reservoir below the water-level, and means constructed and arranged to provide a cover for said reservoir and to support a shoe in the path of the vapor rising from said 60 boiler.

47. A shoe-treating apparatus comprising means arranged to support a shoe for treatment, a heater arranged to underlie a shoe supported by said means, a water reservoir 70 and a boiler arranged in nested relation but thermally insulated from each other and having communication with each other below the water-level, said reservoir and said boiler being arranged to underlie such shoe below 75 the level of said heater, and means arranged to supply hot water from said boiler to said heater by the force of ebullition.

In testimony whereof I have signed my name to this specification.

FREDERICK W. PHILLIPS.
